UNITED STATES PATENT OFFICE.

OWEN J. McGOWAN, OF BROOKLYN, NEW YORK.

RELEASING HOOK.

1,405,056.

Specification of Letters Patent. Patented Jan. 31, 1922.

Application filed March 3, 1921. Serial No. 449,365.

To all whom it may concern:

Be it known that I, OWEN J. McGOWAN, a citizen of the United States, and a resident of the borough of Brooklyn, city of New York, in the county of Kings and State of New York, have invented certain new and useful Improvements in Releasing Hooks, of which the following is a specification.

This invention relates to improvements in releasing hooks and particularly to the type of releasing hook patented in Letters Patent issued to me July 1st, 1919 and numbered 1,308,549.

One of the objects of my present invention is to produce a releasing hook which has all the advantages specified in my Letters Patent above mentioned and in addition provides improved and more readily actuated keying means for securely locking the hook against automatic action, which keying means when in locked or operative position prevents the relative sliding or unlocking movement of the parts of the hook and consequently prevents any pivotal or disengaging movement thereof until this blocking means is removed.

Removal of such blocking means on a plurality of hooks may be readily accomplished by a single man while the strain of the load

30 is on the hook and will thus prepare both hooks for automatic release when the same is relieved from the load, as for example, when a boat to which the hook is connected is waterborne.

35 Another object of my invention is to produce a construction of releasing gear in which a pair of automatically-releasable hooks positioned at opposite ends of a life-boat may be quickly and readily locked

40 against automatic action and may be simultaneously by a single operator unlocked under load so as to cause the automatic releasing features thereof to come into action immediately when the strain of the load is relieved by the boat being waterborne.

Another feature of my present invention enables the body portion of a hook of the type patented as aforesaid to be moved into and locked in fixed upright position during

50 the engaging operation thereby facilitating the hook-engaging and locking operations, and also causing said body portion in the releasing or disengaging operation to be retained in upright locked position for a short period of time and until the hook-portion

entirely falls away therefrom, after which the body or housing will also be permitted to fall inwardly and be out of the way.

In the preferred form of my invention a hook portion, which is pivotally connected to a body-portion or housing so as to be capable of pivotal movement and also has a slight unlocking or sliding movement relatively to the body portion or housing, is provided with means releasable by the pivotal movement of the hook-portion for latching the body portion in upright position and also is provided with pivotally movable keying means for locking such hook parts against relative sliding movement. Means is also preferably provided for simultaneously releasing the pivotally movable keying means on a pair of such hooks to permit such sliding or unlocking movement of the parts so that an automatic release of the hook will occur when the strain of the load is relieved, as for example, when a boat in which a pair of such hooks are mounted is water-borne. The keying means preferably comprises a segment which is preferably pivotally mounted in the body portion and has a bearing portion on which the lower end of the hook portion bears when in operative position.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is an elevation partially broken away of a life-boat suspended from a pair of davits in which a pair of my improved hooks fastened against automatic release are mounted and connected to permit simultaneous unlocking of the fastening means; 100

Fig. 2 is a side elevation partly broken away of my improved hook engaged with a load and with the fastening means in locked position;

Fig. 3 is a similar side elevation partly broken away of my improved hook with the fastening means released and the hook portion just engaging and releasing the locking pawl between the body portion and its bearing;

Fig. 4 is a side elevation similar to Fig. 3 showing the parts in turned-down position; and

Fig. 5 is a rear end elevation of the hook 5 in the position shown in Fig. 2.

Referring now to these drawings, and more particularly to Fig. 1 thereof, 1 indicates a life-boat which, as shown, is suspended from a pair of davits 2 by tackles 10 4 connected with a pair of releasing hooks 5 mounted in the life-boat and, as shown, pivotally mounted on bearings 6' fixed on the upper ends of rods 6 which extend to and are fastened to the keel of the life-boat. 15 In the improved hook of my present invention, each of the releasing hooks 5 embodies (Figs. 2 to 5) a body portion 7 pivotally mounted on the pivot 7' fixed in the bearings 6', and a hook portion 8 pivotally 20 mounted on the pivot 8' fixed in the body portion so as to swing pivotally in relation to such body portion and also to have a slight sliding movement relatively thereto in order to permit inter-engagement and releasing of cooperating locking notches 9 and 25 10 provided respectively in said body and hook portions. The notch 9 is, as shown, formed by undercutting the head or upper end 7 of the body portion and the notch 10 is formed in the outer periphery or nose of 30 the hook portion 8. The relatively sliding movement between the body and hook portion is preferably procured by elongating the pivot-bearing hole 11 and providing a 35 sliding space 7a in the body portion below the hook portion so that the hook portion may slide up and down on the pivot 8' but when the parts are swung on the pivot 8' into inter-engagement and the strain of the 40 load or other pressure is applied on the hook portion 8, the body portion 7 being retained in relatively stationary position on its pivot 7', the hook portion will be moved or slid upwardly relatively to the body portion on 45 the pivot 8' and the locking notches 9 and 10 will be brought into interengagement. So soon, however, as the strain or pressure is relieved from the hook, the hook-portion unless fastened or prevented from falling 50 by keying means will automatically and immediately because of the elongated pivot hole 11 and sliding space 7a be moved by gravity relatively to the body portion a sufficient distance to cause the notches to be unlocked and the parts will also immediately 55 have relative pivotal movement to release the ring of the falls of a life-boat or other load.

As shown, the foot or lower end of the 60 pivoted hook portion 8 is preferably concavely curved at 12 and the sliding space is formed through the body portion below said foot. In this space is pivoted on the pivot 13 supported in the body portion a segmental fastening member or bolt 14 which

is movable beneath and into engagement with the concavely-curved foot of the hooked portion so as to completely and effectively lock the hook portion against any sliding movement when the parts are in engaged position and said segmental bolt is inserted beneath the said foot-portion. Said segmental fastening member or bolt preferably carries releasable latching means, such as the spring-pressed ball 15, for providing a releasable latching engagement between the foot of the hook portion and said segmental fastening or bolt member. 70 75

The segmental fastening members 14 at opposite ends of a lifeboat are preferably 80 provided with radially-extending levers 16 and these levers 16 are connected by a connecting rope or like connection 17 which is passed over pulleys 18—19—20 and 21 and extends along the side of the boat to a common operating handle 22.

In the preferred embodiment of my invention shown said body portion is preferably releasably retained in upright position while the parts are engaged, during the engaging operation and during the pivotal disengaging movement of the hook portion in relation to the body portion, and the hook-portion is weighted at 12a to cause an overbalancing thereof and a quicker pivotal 90 or disengaging movement. 95

Said body portion is relatively held in upright position by cooperation of a pin 23 mounted in ears 24 on said body portion which abuts against the stationary base 100 bearing 6' on one side and a pivoted pawl 25 which is mounted on the pivot 13 carried by the said body portion, and this pawl 25 is released by the engagement of the weighted portion 12 of the hook portion during its 105 pivotal movement about the pivot 8', whereby the body portion is when the pawl is so released carried by the weighted hook portion and swung about the main pivot 7' into the folded-down position of the releasing 110 hook shown in Fig. 4.

The pawl 25 in the preferred embodiment shown is mounted in a housing formed therefor in the fastening member or bolt and has a weighted nose which causes the same to 115 move by gravity into locking engagement with its notch when the body portion is moved to upright position.

A lanyard 27 is preferably connected to the upper end of the hook portion 8 for 120 throwing the hooked portion to upright or engaging position.

The operation of the hook is as follows:—

Assuming that the hook is in the position shown in Fig. 4, the body portion is shoved 125 into upright position whereupon the pawl 25 will fall into a notch 26 and retain the same in such position. The falls ring is placed over the body portion; the lanyard 27 is employed to swing the hook portion about the 130

pivot 8' and to hold it up with the locking notches in engagement until either the pivoted segmental fastening or bolt member is swung into place and latched or until the 5 strain of the load is applied on the hook portion to retain the locking notches 9 and 10 in interengagement. When the fastening member or bolt is swung into place the falls rings will be securely locked in the hook. 10 When now it is desired to release a boat having a pair of these hooks from the falls, it is only necessary to pull the common operating handle 22 or connecting rope 17 whereupon both fastening segments will be simultaneously 15 removed from locking engagement with the foot portion and the hook will, although still locked by the strain of the load, be capable of immediate automatic release immediately upon relieving such strain, as 20 for example, when the boat is waterborne. When so released, the hooked portion slides downwardly relatively to the body to release the inter-engagement of the notches 9 and 10 and then moves pivotally into the position 25 shown in Fig. 3 in which the pawl 25 is released by the weight portion 12^a, after which the entire hook which is overbalanced by the weighted hook portion will fall over into the position shown in Fig. 4 and will then 30 be out of the way.

Having described my invention I claim:—

1. A releasing hook embodying, in combination, a body portion, a hook portion, said parts being relatively movable pivotally into 35 contact with each other and also having independent relative movement for locking and releasing such contacting parts; and pivotally-movable means associated with said parts for fastening the same against said 40 relative independent movement to retain such parts in locking engagement, and means for releasing such pivotally-movable fastening means.

2. A releasing hook embodying, in combination, a body portion, a hook-portion movable pivotally into contact with the body portion and also having relative sliding movement in relation to said body portion for locking and releasing said body and hook 45 parts; pivotally-movable means associated with said parts for fastening the same against sliding movement to retain such parts in locking engagement and means for releasing such pivotally-movable fastening 50 means.

3. A releasing hook embodying, in combination, a body portion, a pivot carried thereby, a hook portion movable pivotally on said pivot into contact with the body portion and also having relative sliding movement in relation to said body portion for locking and releasing said parts; another pivot carried 55 by said body portion; fastening means pivoted on said pivot for fastening the parts against sliding movement to retain such

parts in locking engagement and means for releasing such pivotally-movable fastening means.

4. A releasing hook embodying, in combination, a body portion, a hook portion movable pivotally into contact with the body portion and also having a relative sliding movement in relation to said body portion for locking and releasing said parts and pivotally movable means for fastening said parts against sliding movement comprising a segmental block pivotally mounted within the body portion and means for releasing said segmental block. 70

5. A releasing hook embodying in combination a body portion, a hook portion movable pivotally into engagement with the body portion and also having a relative sliding movement in relation to said body portion for locking and releasing said parts 80 and pivotally movable means for fastening said parts against sliding movement comprising a segmental block pivotally mounted within the body portion and a lever connected to said segmental block for releasing the same from fastening engagement. 90

6. A releasing hook embodying, in combination, a body portion, a hook-portion movable pivotally into contact with the body portion and also having a relative sliding movement in relation to said body portion for locking and releasing said parts and pivotally-movable means for fastening said parts against sliding movement comprising a segmental block pivotally mounted within the body portion, means for releasing said segmental block and means for releasably latching the segmental block to said hook portion. 95

7. A releasing hook embodying, in combination, a body portion pivotally mounted at its lower end, a hook portion, said parts being movable pivotally into contact with each other and also having a relative sliding movement for locking and releasing said contacting parts and means for releasably latching said pivoted body portion in upright position. 105

8. A releasing hook embodying, in combination, a body portion pivotally mounted at its lower end, a hook portion, said parts being movable pivotally into contact with each other and also having a relative sliding movement for locking and releasing said contacting parts, means for releasably latching said pivoted body portion in upright position, pivotally-movable means associated with said parts for fastening the same against relative sliding movement to retain such parts in locking engagement, and means for releasing such pivotally-movable locking means. 115

9. A releasing hook embodying in combination a body-portion pivotally mounted at its lower end, a hook-portion movable piv- 130

totally into contact with the body-portion and also having a relative sliding movement in relation to said body portion for locking and releasing said parts, means for releasably latching said body portion in upright position, pivotally-movable means for fastening the said parts against sliding movement comprising a segmental block pivotally mounted and housed within the body portion, means for releasing said segmental block and means for releasably latching the segmental block to said hook portion.

10. In apparatus for raising and lowering life-boats embodying, in combination, a pair of releasing hooks, one of which is connected to the lowering and raising apparatus at each end of a lifeboat and each comprising a body portion, a hook portion movable pivotally into contact with the body portion and 15 also having relative sliding movement in relation to said body portion for locking and releasing said parts and pivotally-movable means associated with said parts for fastening the same against sliding movement to 20 retain such parts in locking engagement, and a connection arranged in the boat and operatively connected to the fastening means of said opposite hooks for simultaneously 25 releasing such pivotally-movable fastening means to permit automatic release of the 30 means to permit automatic release of the

hooks when the strain of the load is released.

11. A releasing hook embodying in combination a body-portion pivotally mounted at its lower end, a hook portion movable pivotally into contact with the body-portion and also having a relative sliding movement in relation to said body portion for locking and releasing said parts, means for releasably latching said body portion in upright 35 position, pivotally-movable means for fastening the said parts against sliding movement comprising a segmental block pivotally mounted and housed within the body portion, means for releasing said segmental 40 block, means for releasably latching the segmental block to said hook portion and a connection arranged in the boat and operatively connected to the fastening means of said opposite hooks for simultaneously 45 releasing such pivotally-movable fastening means to permit automatic release of the hooks when the strain of the load is released.

In witness whereof, I have signed my name to the foregoing specification in the 50 presence of two subscribing witnesses.

OWEN J. McGOWAN.
